UNITED STATES PATENT OFFICE.

PETER H. HERSHEY, OF DAUPHIN, PENNSYLVANIA.

WALL FORM.

Application filed June 24, 1921, Serial No. 420,086. Renewed December 22, 1922.

To all whom it may concern:

Be it known that I, PETER H. HERSHEY, a citizen of the United States, residing at Dauphin, in the county of Dauphin and 5 State of Pennsylvania, have invented new and useful Improvements in Wall Forms, of which the following is a specification.

The object of my present invention is the provision of an improved form for facilitating the construction of those concrete walls that are characterized by inner and outer portions separated by an intervening 10 chamber or dead-air space.

To the attainment of the foregoing, the 15 invention consists in the improvement as hereinafter described and definitely claimed.

In the accompanying drawings, forming part of this specification:—

Figure 1 is a side elevation of a form constructed in accordance with my invention.

Figures 2 and 3 are sections taken in the planes indicated by the lines 2—2 and 3—3, respectively, of Figure 1.

Figure 3^a is a perspective of a portion of 25 the cap member of the form.

Figure 4 is a longitudinal vertical section on the line 4—4 of Figure 2.

Figure 5 is a detail perspective of one of the form locks.

Figure 6 is a plan showing the invention embodied in mitered corner forms.

Similar numerals designate corresponding parts in Figures 1-5 to which reference will first be made.

Among other elements my novel form includes a cap member 1, notched at 2 in its edges, and having longitudinal grooves 3 in said edges. The said form also comprises inner upright plates 4 and 5, and outer up- 35 right plates 6 and 7, in combination with locks, preferably two in number, one of which locks is best shown in Figures 3 and 5. Each of the said locks comprises members 8 and 9, of inverted U-shape, arranged

40 in lapped relation, and each also comprises a central vertical bar 10 with a pointed upper end 11, and toggle links 12 interposed between and pivotally connected to the bar 10 and the inner uprights of the members 8 and 9. Connected to and interposed between the bars 10 of the two locks is a longitudinal bar 13, on the center of which is an upright bar 14.

It will be readily apparent from the fore- 50 going that with the uprights of the members 8 and 9 connected to the plates 4—7, Fig-

ures 1-3, vertical movement of the bars 10 of the locks to the positions shown in Figures 3 and 5, will be attended by setting or clamping of the plates 5 and 7 against one 60 concrete or plastic wall portion 20, and setting or clamping of the plates 4 and 6 against a similar wall portion 21, said wall portions being separated by an intervening space or chamber 22. It will also be apparent that on vertical movement of the bars 10 from the position shown in Figures 3 and 5, the plates 5 and 7 will be moved away from the wall portion 20, and the plates 4 and 6 will be moved away from the wall portion 21; the uprights of the member 8 being connected to the plates 5 and 6, and the uprights of the member 9 being connected to the plates 7 and 4. The said uprights of the members 8 and 9 are disposed in the 65 notches 2 of the cap member 1, when said cap member 1 is arranged as shown in Figure 3, and its grooves 3 or rather the walls at the inner sides of the grooves will hold the plates 4 and 5 against movement toward 70 each other. It will also be noted that the points of the upright bars 10 will be accommodated in the apex of the cap member 1 which is preferably angular in cross-section.

The cap member 1 is connected, pivotally 85 or otherwise, in permanent manner at 30 to the upper end of the bar 14 so that by lifting the cap member, the locks may be contracted to release the plates 4—7 and by lowering the cap member the locks may be 90 expanded to set or clamp the said plates. Sufficient of the plates 4—7 are employed to go around a building, and when properly used the forms made up of said plates enable the walls to support and brace each 95 other.

As shown in Figure 6 two forms of the general construction described will be employed for a corner 1; the contiguous ends of the said forms being mitered as indicated 100 by 40.

For instance when the bars 10 are connected to the cap member 1 at 31, Figures 3 and 4, the bar 13, upright 14 and connection 30 may be omitted.

The essential feature of my invention is the simultaneous locking or binding of the plates against opposite sides of two spaced walls.

I have entered into a detailed description 110 of the construction and relative arrangement of parts embraced in the present and

preferred embodiment of my invention in order to impart a full, clear and exact understanding of the said embodiment. I do not desire, however, to be understood as confining myself to the said specific construction and relative arrangement of parts inasmuch as in the future practice of the invention various changes and modifications may be made such as fall within the scope 10 of my invention as defined in my appended claims.

Having described my invention, what I claim and desire to secure by Letters-Patent, is:—

- 15 1. A building form comprising inner plates and outer plates, locks each having inverted U-shaped members connected to said plates and also having an upright bar and toggle links between said bar and members, and a cap member connected with said locks.
- 20 2. A building form comprising inner plates and outer plates, locks each having inverted U-shaped members connected to said plates and also having an upright bar
- 25

and toggle links between said bar and members, and a cap member connected with said locks; said cap member shaped to interlock with and prevent inward movement of the inner plates.

3. A building form comprising inner plates and outer plates, and a lock having inverted U-shaped transverse and lapped members connected to said plates and also having an upright bar and toggle links between said upright bar and the inner portions of the U-shaped members.

4. A building form comprising inner plates and outer plates, and a lock having inverted U-shaped transverse and lapped members connected to said plates and also having an upright bar and toggle links between said upright bar and the inner portions of the U-shaped members, in combination with a cap member to interlock with two of the said plates and a connection between said cap member and the upright bar.

In testimony whereof, I affix my signature.

PETER H. HERSHÉY.
